UNITED STATES PATENT OFFICE

ANDRÉ VARAUD, OF GENEVA, SWITZERLAND

SUPERSENSITIVE HEAD IMPACT FUSE

Application filed June 10, 1931, Serial No. 543,447, and in Switzerland June 19, 1930.

My invention relates to a supersensitive head impact fuse for artillery projectiles.

In mechanisms of this kind the head of the striker pin is pushed by air pressure during 5 the flight of the projectile and means must be provided to retain the same. It has been proposed to use a spring, a transversal pin of pre-determined strength. It has also been proposed to protect the striker head by a 10 thin cap which breaks on impact.

According to my invention, the head of the striker is in the form of an inverted cup-shaped member having its open end closed by a thin metallic diaphragm which may 15 centrally bear against a tubular member through which is passed the striker pin. When the striker head receives the least blow the diaphragm is broken and the pin acts on the detonator.

20 In the annexed drawings:

Fig. 1 is a longitudinal section of the fuse in the position in which it may be handled.

Fig. 2 is a similar view of the fuse during 25 its travel through the gun.

Fig. 3 shows the fuse during the flight of the projectile.

Fig. 4 shows the fuse during the impact.

The fuse comprises a body 1, a cap 2, a 30 striker pin 3, a detonator support 4 with its spring 4a and a centrifugal bolt 5.

The striker head 8 is in the form of an inverted cup-shaped member having its open end closed by a thin metallic diaphragm 7 for instance of soft copper. Diaphragm 7 is 35 of course centrally apertured to accommodate the striker pin 3.

A tubular member 6 is disposed around pin 3 and so as to bear against diaphragm 7 (Fig. 1).

40 The device works as follows:

In the position of Fig. 1, the striker pin is maintained by diaphragm 7. Should it eventually receive a hard blow, the diaphragm would be only slightly depressed, the pin being locked by bolt 5 as in the case of Fig. 2. The projectile can thus be safely handled.

45 When the projectile is fired in the gun, pin 3 tends to depress diaphragm 7 by in-

ertia. But breakage of the latter is prevented by bolt 5 (Fig. 2).

During the flight, the rotation of the projectile causes bolt 5 to laterally escape (Fig. 3). The striking system is then only 55 maintained by diaphragm 7 the strength of which is just sufficient to resist the action of air pressure against head 8.

When the projectile encounters any object, whatever slight it may be, the blow is 60 sufficient to cause diaphragm 7 to open upwardly (Fig. 4). Pin 3 is thus free to sink and to strike the detonator. The advantage of this device is that when the diaphragm is 65 sufficiently opened, its resistance is negligible and the percussion is not braked. This may be amplified by conforming member 6 as shown, with a slightly conical inverted portion at its upper end, whereby (Fig. 4) the 70 opened tubular central part of diaphragm 7 is freed from any friction against the body of member 6.

I claim:

1. A supersensitive head impact fuse for projectiles comprising in combination a fuse 75 body; a detonator within said body; a striker pin co-axial with said body and adapted to strike said detonator on sinking into said body; a safety bolt adapted to maintain said striker pin against inertia 80 during the firing of the projectile; a striker head in the form of an inverted cup-shaped member fixed at the free end of said striker pin; a tubular member fixed to the fuse body co-axially with said striker pin, said member 85 being sufficiently restricted in diameter to enter freely said inverted cup-shaped striker head, when said striker pin is sunk into the fuse body; and a diaphragm closing the open 90 end of said striker head, said diaphragm being centrally provided with a hole of a diameter such that said pin may pass freely through said diaphragm but that said tubular member bears against the same and thus 95 prevents said striker head from sinking under the action of air pressure, the strength of said diaphragm being however insufficient to resist even a slight blow on said striker head.

2. A head impact fuse as claimed in claim 100

1 wherein the external diameter, of the tubular member is somewhat enlarged at its upper end, whereby when said diaphragm has been opened upon an impact, it is free from
5 contact with said tubular member and thus does not exert any braking action on the striking system.

In testimony whereof I affix my signature.

ANDRÉ VARAUD.
